CLAIM

The ornamental design for a storage container, as shown and described.

DESCRIPTION

FIG. 1 is a perspective view of a storage container showing our new design;

FIG. 2 is a rear perspective view of the storage container illustrated in FIG. 1;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings showing the storage container illustrate the portions of the storage container that form no part of the claimed design.

The dash-dot-dash lines in the drawings represent boundary lines between claimed and unclaimed areas of the storage container.
